METHOD OF PRODUCING HIGH-FREQUENCY OSCILLATORY CURRENTS.

1,216,646.

Specification of Letters Patent. Patented Feb. 20, 1917.

Application filed October 14, 1911. Serial No. 654,741.

To all whom it may concern:

Be it known that I, JAMES C. ARMOR, a citizen of the United States, and a resident of Ingram, in the county of Allegheny and State of Pennsylvania, have invented a new and useful Improvement in Methods of Producing High-Frequency Oscillatory Currents, of which the following is a specification.

10 My invention relates to methods and means of producing high frequency oscillatory currents from either direct or alternating current sources, and it has particular reference to the production of high-potential waves of 15 high periodicity such as are adapted for use in wireless telegraphy, telephony and similar arts.

One object of my invention is to provide an improved method of producing waves or 20 currents of the above indicated character which shall be simple to practise and particularly effective in accomplishing the desired results.

Another object is to eliminate to a great 25 degree the energy losses incident to the methods heretofore employed and to obtain sustained oscillatory waves or currents which will permit of greater transmission distances and more accurate "tuning" than 30 has been possible in the prior art. By "sustained" waves or currents, I refer to waves or currents the oscillations of which are of uniform or equal amplitude.

Still another object is to produce trains or 35 groups of unidirectional intermittent impulses which shall be equally spaced in time and of high periodicity, and to employ such impulses to set up sustained trains or groups of oscillatory currents of the character indicated.

In the past, high frequency oscillatory currents or waves have been secured and employed successfully in wireless work, but difficulties and limitations have been encountered by reason of the fact that the waves were not continuously and regularly sustained or were produced in groups or trains of very short time periods.

It is well known that when a condenser is 50 discharged across a spark gap, the discharge is oscillatory in character and of extremely high frequency and, moreover, that the oscillations rapidly decrease in amplitude and are damped out. At the present time, in 55 wireless work, a rapid succession of such

discharges is usually effected and the high-frequency oscillations of rapidly diminishing amplitude just referred to are employed to set up a series of trains or groups of waves in the working circuit. Obviously, 60 these groups of waves are of the same character as the discharges, that is, of very short duration and of rapidly diminishing amplitude. Only a few of the first oscillations are effective in producing useful results and 65 the energy of remaining waves is spent or dissipated in useless work.

According to my present invention, I propose to greatly increase the number of condenser discharges per second and to rupture 70 each discharge at a predetermined time, preferably when the first oscillatory wave reaches its zero value, although I do not wish to be limited in this respect. In this way, if a direct current source is employed, 75 a succession of equally spaced unidirectional intermittent impulses or half waves of high frequency is obtained, which may be employed to set up oscillatory currents in a working circuit containing inductance and 80 capacity in proper and predetermined proportions. In case the source of energy employed for charging the condenser is alternating in character, there will be a train of unidirectional intermittent impulses or 85 waves of equal amplitude and of positive value during one half cycle of the source of energy and a train of similar waves of negative value during the other half cycle thereof. 90

The resulting oscillatory currents or waves will, of course, be sustained and will be of the same character irrespective of whether the impulses be positive or negative, the only effect being that they will be 95 broken up into groups or trains. However, the duration or length of these groups or trains will be very much greater than those secured heretofore so far as I am aware, and, by reason thereof, in connection with 100 the sustained character of the oscillations, a material advance in the art of wireless signaling will be effected which will increase transmission distances and the accuracy of signaling. 105

In order to rupture the discharges between the spark gap terminals at a predetermined time, I employ a jet or stream of gas or fluid of very high velocity which is directed across the gap and serves the purpose of 110

breaking the low-resistance path established by the discharge between the gap electrodes and thus rupturing the discharge. Moreover, I prefer that the velocity of the stream bear such a relation to the discharge frequency, the width of the gap terminals, the sparking distance and the natural time period of the circuit that a rupture of the discharge after the first half cycle of the discharge wave is insured. Thus, an oscillatory discharge is prevented and a series of like unidirectional impulses of high periodicity is obtained. Hence, the energy of the remaining discharge oscillations of diminishing amplitude that has hitherto been dissipated, is conserved, whereby a considerably better efficiency is secured and greater power is delivered to the working circuit.

Moreover, by rupturing the discharge oscillations after the first half cycle of the discharge wave, the time interval heretofore occupied by the following useless oscillations is advantageously employed as the condenser begins to charge immediately after discharge, so that the periodicity or number of condenser discharges per second may be greatly increased, depending, of course, upon the capacity of the condenser and other circuit constants.

Manifestly, various structural devices and arrangements of circuits and apparatus which embody the principle of my invention and secure, to a greater or less extent, the advantages thereof, may be employed in practising my invention and, without attempting to illustrate all the forms, modifications and arrangements of which my invention is susceptible, I will describe several typical embodiments thereof, as illustrative of the apparatus which I now consider to be best adapted to produce the desired results. It should be understood, however, that, broadly considered, my invention is not limited to the specific apparatus and arrangements set forth but will permit of many variations which do not materially change the mode of operation and the results secured.

In the accompanying drawings Figure 1 is a diagrammatic view illustrating an arrangement of circuits and apparatus which embodies my invention. Fig. 2 is a view similar to Fig. 1 showing a slightly modified arrangement of circuits, Figs. 3 and 4 illustrate other modifications embodying my invention, and Fig. 5 discloses a still further modification of my invention.

Referring particularly to Fig. 1, a source of energy 1-2 is adapted to deliver electrical energy to a spark gap 3 comprising a plurality of spark electrodes 4, through circuit conductors 5 and 6 which severally contain a variable section of resistance 7 and of inductance 8 connected in series

therewith, said spark gap 3 being shunted by a circuit including a variable condenser 9 and an adjustable inductance coil 10.

The source 1-2 may be of direct or alternating current, as desired, and the condenser 9 and inductance coil 10 may be of any construction that is well known to those skilled in the art. Furthermore, I do not wish to be restricted as to the specific structure of the electrodes 4, although I prefer to employ very thin disks of a suitable metal and to provide means whereby said electrodes may be rotated at a considerable speed.

In proximity to the coöperating electrodes 4, is located a nozzle 11 through which a stream of gas or fluid of very high velocity is discharged, said stream being directed across the discharge path between the electrodes 4 in order to be effective in positively rupturing the discharge in a manner to be hereinafter set forth.

It is well known that if a condenser be connected in shunt to a suitable spark gap and be charged from a constant potential source, that the spark gap will always break down at the same voltage and the discharges will occur at regular intervals of time, depending upon the capacity of the condenser and other circuit constants. This is true only for a comparatively small number of discharges per second under the usual conditions, above which a continuous arc is maintained. However, according to my invention, by providing a high-velocity fluid jet to positively rupture the discharges at a predetermined time and, by suitably choosing the capacity of the condenser 9, and the values of the resistance sections 7, any desired number of discharges per second may be obtained across the spark gap 3.

I contemplate the production of oscillatory currents or waves having a frequency as high as two hundred thousand oscillations per second, although currents of greater or less periodicity may be obtained, and I therefore employ a condenser 9 of very low capacity in order to secure the desired number of discharges per second.

Furthermore, it is well known that when a condenser discharges across a gap, a low resistance path is established between the spark electrodes which becomes conducting in character after the initial spark. By means of the jet of gas or fluid 11, I propose to increase the length of this low-resistance path within a given period to such an extent that the oscillatory discharge wave will be ruptured after the first half cycle or when it reaches its first zero value.

More properly I eliminate any "cycle" at all; and I open the circuit completely at a predetermined time and instantly upon the first discharge, by the mechanical motion of the medium between the electrodes. The

action is not analogous to cooling, in which a conducting path gradually disappears by becoming less and less conducting.

To explain the matter further it may be pointed out that in the prior art it has been understood, both as to a so-called spark gap, and as to an arc, that the discharge was oscillatory. That is, the voltage on one electrode is built up until it is sufficient to break down the intervening insulating medium, whereupon a discharge occurs which has the immediate effect of heating the medium or creating a metal vapor which becomes a conducting path, and acts as a conductor for a reflex passage of electricity in the other direction. The action of the discharge is like the motion of a pendulum, every movement in one direction being followed by a reflex movement in the other direction by reason of the overcharge of the opposite electrode, and the electric resiliency of the circuit containing inductance. In the so-called quench gap systems in the prior art various cooling devices have been employed to quicken the deterioration of the conducting qualities of the path of vapor established by the original discharge, but so long as the oscillatory discharge continues it continues on the same path. In other words the cooling of air blast and magnetic blast was a mere device to decrease the conducting power of the path through which the discharge was oscillating.

In my system, on the other hand, it should be noted at the outset, there is no oscillating passage at all, and cooling has nothing to do with the action whatever. The discharge occurs when the potential or electric pressure has been built up to a degree which allows the overcoming of the resistance of a moving path of intervening medium, but the velocity of the medium is so great that when the discharge has passed once, the path itself has disappeared, being elongated to such degree that it is of higher resistance than the new intervening medium interposed in the interim. Any vapor created by the discharge has become dissipated, and is no longer accessible as a path for any reflex discharge. The result is a regulated series of dead-beat discharges in one direction only. In these remarks I of course refer to what is properly called high frequency oscillation as distinguished from the ordinary alternating current.

In order to accomplish this result, the velocity of the stream must necessarily bear a more or less definite relation to the width of the gap terminals, the number of discharges per second, the sparking distance and the natural oscillation period of the shunt circuit. In practice, it will be found expedient to determine the proper velocity by experiment, but, in order to show that this velocity is related to the elements referred to, I will present a rough calculation of the

same, it being understood that the values assumed and the result secured are only illustrative.

For example: Let it be assumed that the resistance section is 7 and the capacity of the condenser 9 be so adjusted that 200,000 discharges per second are obtained, which means that the time interval for a single charge and discharge is $\frac{1}{200,000}$ of a second. Let it be further assumed, for best operating conditions and results, that the actual time of a single discharge to the total time interval of a single charge and discharge should be in the ratio of 1 to 3. This assumed ratio, of course, will vary considerably, dependent upon conditions, and may be best determined by experiments. If then, the time of discharge is to be a third of the total time interval of charge and discharge, and if the discharge itself is to be ruptured after the first half cycle, it is evident that the time required per half cycle is $\frac{1}{600,000}$ of a second. In order to meet this condition, it is merely necessary to adjust the shunt circuit to the proper natural oscillation period by means of adjustments of the inductance with respect to the capacity of the condenser 9.

If now the sparking distance between the electrodes 4 be assumed to be $\frac{1}{10}$ of an inch, it is evident that if the low resistance path established between said electrodes be drawn out to a length that is roughly some multiple of the sparking distance in the period of discharge, a rupture of the discharge will be effected after the first half cycle, or at the zero point of the wave. Obviously, the proper multiple requires experimental determination but, for the present purpose, it will be assumed that the value is 4. The required velocity of the stream in feet per second should then be approximately equal to the product

$$\frac{1}{100} \times \frac{4}{2} \times \frac{1}{1} \text{ divided by } \frac{1}{600,000} \text{ feet per second.}$$

or approximately 1000 feet per second. Such a velocity is not impracticable as, with certain gases or fluids, hydrogen for instance, velocities of 5000 feet per second may readily be secured.

It should be borne in mind that calculations of this character are not sufficiently accurate for practical purposes but serve merely to give an approximation of the required velocity and to show that it is related to the elements specified. Obviously, for the assumed conditions and values, a stream of greater than the calculated velocity would accomplish the desired result.

Assuming then that the velocity of the stream is of the proper value and that a direct current source of energy, is employed, it is evident that a rapid succession of unidirectional intermittent impulses of equal

amplitude are secured and that these impulses are equally spaced in time and correspond to a frequency of 200,000 per second. These high frequency impulses are diverted 5 into the shunt circuit containing the condenser 9 and the inductance coil 10 and are prevented from being reflected upon the source 1-2 by means of the inductances 8 which tend to choke back the high-frequency waves and to maintain constant circuit conditions.

If an alternating current source be used, a group or train of unidirectional intermittent impulses of a positive value will be 15 secured corresponding to the first half cycle of the alternating source, while similar impulses of an equal and negative value will be established for the last half cycle of the source.

20 In some cases, better results may be secured by the employment of an auxiliary condenser 12 which is connected in shunt to the spark gap 3, as shown in Fig. 2, and, in such an event, the relative capacities of 25 the condensers 9 and 12 and the amount of inductance 10 should be determined experimentally.

Reference may now be had to Fig. 3 which shows an arrangement of circuits 30 similarly to that of Fig. 1 and, in addition, a closed working circuit which is inductively associated with the inductance coil 10 and contains a variable condenser 13 and an adjustable inductance coil 14. The coil 35 15 constitutes a secondary member of a transforming device 16, the primary member of which is the inductance coil 10.

With this arrangement of connections and apparatus, it is evident that if a series 40 of unidirectional intermittent impulses of equal amplitude and of a high frequency be established through the shunt circuit containing the primary inductance coil 10 and the condenser 9, a series of sustained oscillatory currents or waves of a corresponding 45 periodicity will be set up in the working circuit, provided the relative proportions of inductance and capacity therein be adjusted for the proper natural oscillation 50 period. This working circuit is termed "resonant" to the particular frequency, although it is usually not strictly so. In employing the term "resonant" in this connection, I mean that the relative proportions 55 of inductance and capacity in the circuit are such as to correspond to the natural time period of the current of the desired frequency.

In case the source 1-2 be alternating in 60 character, the oscillatory currents or waves produced in the working circuit will occur in groups or trains by reason of the changes in value of the impulses produced in the shunt circuit. Moreover, if the working circuit 65 be "tuned" or the capacity and inductance

be mutually adjusted for the particular frequency of the intermittent impulses, it will be found that the oscillatory currents developed therein will exert a tendency toward smoothing out any slight irregularities in the periodicity of the impulses and will keep them in "step."

In Fig. 4 a somewhat modified arrangement is shown which differs from that shown in Fig. 3 in that the conductor 6 is 70 connected to the shunt circuit at a point 17 between the inductance 10 and the main condenser 9, which is shunted by an auxiliary condenser 12. With this arrangement, the inductance 10 is not effective during periods of charge and the energy is delivered directly to the condensers 9 and 12, whereas, during the period of discharge, it is included in the circuit, and is traversed by the rapid succession of intermittent impulses.

Referring now to Fig. 5, which is a perspective view of a pair of coöperating rotating electrodes which may, in some cases, be employed to advantage in practising my 90 invention, the spark gap 3 embodies a plurality of thin disk electrodes 4 which are adapted to be rotated from a driving shaft 18 by means of suitable pulleys 19, 20 and 21 and belts 22 and 23 in a well known manner. Shafts 24 and 25 to which the electrodes 4 are respectively attached, are rotatably supported in bearing members 26 and 27 and are respectively provided with slip rings 28 and 29 coöperating contact fingers 30 and 31 by means of which electrical connections with conductors 32 and 33 are made.

When employed in connection with a nozzle, as hereinbefore set forth, the electrodes 105 4 should be extremely thin and should be rotated at moderate speeds in the manner shown in Fig. 5. However, it may be found advisable to dispense with the nozzle 11 and rotate the electrodes 4 in opposite directions at very high predetermined speeds in a suitable medium whereby the high velocity stream or jet of fluid, hereinbefore referred to, may be produced by the electrodes themselves, it being understood that if sufficient peripheral speed be secured, a portion of the medium adjacent to the edges of the electrodes will be set in motion and carried around therewith. In this way, the required high velocity jet or stream is produced, 110 120 which acts in substantially the same manner as that delivered from the nozzle 11, as shown and described with respect to the Figs. 1, 2, 3 and 4.

These and other modifications in the arrangement of circuits and apparatus may be made within the spirit and scope of my invention, and I desire that only such limitations shall be imposed as are indicated in the appended claims.

I claim as my invention:

1. The method of producing oscillating currents of high frequency by passing a current through a circuit containing a gap, subjecting said gap to the effect of an insulating medium moving between the electrodes thereof to vary the resistance of the path at such speed as to prevent oscillation, and inducing in a second and coupled circuit an oscillating current by the influence of said high frequency intermittent discharges, substantially as described.
2. The method of producing regularly spaced intermittent non-oscillatory electric currents of high frequency which comprises passing a current through a circuit across a gap between two electrodes and positively interrupting said gap by mechanically moving an insulating medium between the electrodes, with sufficient rapidity to make the electric discharges dead-beat, or uni-directional.
3. The method of producing non-oscillatory high frequency intermittent currents by passing a current through a circuit containing a gap causing discharges across the gap, subjecting the gap to the effect of a moving insulating medium having such velocity as to prevent oscillation and regulating the frequency of discharge in part by varying the velocity of the medium between the electrodes.
4. The method of producing high frequency oscillatory currents by induction from another circuit, by exciting that other circuit with direct current adapted to jump a gap therein, subjecting said gap to the effect of an insulating medium moving therethrough at such speed as to prevent oscillation, and regulating the frequency of such intermittent discharges in part by varying the velocity of the medium, substantially as described.
5. The method of producing high frequency oscillatory currents by induction from another circuit by creating high frequency uni-directional non-oscillating discharges in that other circuit, including the step of in part governing the rate of discharge between two electrodes in said primary circuit by subjecting them to the influence of a moving stream of insulating medium, whereby the path of discharge is always longer than the direct distance between the electrodes and will depend for its length upon the velocity of said insulating medium therethrough.

In testimony whereof, I have hereunto subscribed my name this 12th day of Oct., 1911.

JAS. C. ARMOR.
